UNITED STATES PATENT OFFICE.

FRANCIS HODGKINSON, OF EDGEWOOD PARK, PENNSYLVANIA, ASSIGNOR, BY MESNE ASSIGNMENTS, TO THE COLONIAL TRUST COMPANY, TRUSTEE, OF PITTSBURGH, PENNSYLVANIA, A CORPORATION OF PENNSYLVANIA.

GOVERNING MEANS FOR ENGINES.

1,136,910.

Specification of Letters Patent.

Patented Apr. 20, 1915.

Application filed August 27, 1910. Serial No. 579,243.

To all whom it may concern:

Be it known that I, FRANCIS HODGKINSON, a subject of the King of Great Britain and Ireland, and a resident of Edgewood Park, 5 in the county of Allegheny and State of Pennsylvania, have made a new and useful Invention in Governing Means for Engines, of which the following is a specification.

My invention relates to governing means 10 for turbines or other fluid pressure engines; that is to means for delivering variable amounts of fluid to an engine for the purpose of controlling its operation.

An object of my invention is to produce 15 means for exerting a closing force on a fluid delivery valve, forming a part of such a governing means, thus forcibly holding it to its seat and reducing the chance for leakage, and for automatically overcoming 20 or removing the closing force prior to the time of opening the valve so that it may be easily opened with a small expenditure of energy.

A further object is to produce a turbine or 25 engine governing mechanism employing a normal load valve and an overload valve, and in which means are utilized for exerting a closing force on the overload valve during normal loads, and for removing or overcom- 30 ing the closing force during overloads so that the valve may be operated with ease.

A further and more specific object is to produce a normal load valve and overload valve, with which pressure actuated means 35 are employed for holding the overload valve firmly on its seat with considerable force during normal loads, and for automatically overcoming the closing force on the valve when the proper time for opening the valve 40 arrives.

These and other objects I attain in a controlling mechanism embodying the features herein described, and illustrated in the drawings accompanying this applica- 45 tion and forming a part thereof.

In the drawings, Figure 1 is a diagrammatic arrangement of governor actuated valves embodying my invention, the valves and valve casing are shown in section for 50 convenience of illustration. Fig. 2 is a section along the broken line II-II.

The embodiment of my invention illus-

trated is shown in connection with a normal load valve 4 and an overload valve 5. The arrangement of the valves is such as 55 may be employed in controlling the delivery of motive fluid to the initial stage of a turbine and through a by-pass passage to a stage of lower pressure. It may also be employed for delivering motive fluid to a tur- 60 bine or engine, which is arranged to receive fluid from one valve during normal loads and an increased supply of fluid through two or more valves during overloads; or, it may be employed in connection 65 with engines or turbines in which a number of successively opening valves are employed.

The valves illustrated are inclosed within a single casing 6, which is so arranged that all of the motive fluid traversing the cas- 70 ing first passes the valve 4. The casing is divided, by suitably arranged diaphragms 7 and 8, into chambers 9, 10 and 11. The chamber 9 communicates through an inlet port 12 and piping (not shown) with a 75 source of fluid pressure and forms in effect a steam chest for the valve 4. The valve 4 is shown as a balanced puppet valve and controls the delivery of fluid from the chamber 9 to the chamber 10 through a port 80 provided in the diaphragm 7. The chamber 10 is provided with a port 13 which may communicate with the initial stage of a turbine through suitable piping 14. This chamber is in effect a steam chest for the 85 valve 5, which, like the valve 4, is illustrated as a balanced puppet valve and controls the delivery of fluid from the chamber 10 to the chamber 11 through a port formed in the diaphragm 8. The chamber 90 11 is provided with a port 15, which may communicate with a secondary or low pressure stage of a turbine through suitable piping 16.

For convenience of description, I will 95 hereinafter consider the valves, the valve mechanism and the governing device illustrated, as forming a part of the governing mechanism of a turbine.

The valves 4 and 5 are shown in connec- 100 tion with a speed responsive governor 17 and a system of links and levers actuated by the governor for operating the valves. The governor and the valve operating mech-

anism illustrated are more or less diagrammatic, and it will be understood that improved and well known means may be employed for utilizing the varying positions of the centrifugal balls 18 of the governor in actuating the valves. The valve 4 is provided with a valve stem 19, which is shown pivotally connected to a bell-crank lever 20, which is operated through a link 21 and bell-crank lever 22 by the reciprocating sleeve of the governor 17. The valve 5 is provided with a valve stem 23, which extends upwardly through a cylinder 24 and is pivotally connected to a bell-crank 25, which is connected to the link 21 by a rod 26. The arrangement is such that the valve 4 will be fully open—that is, the port opening will be such that the stream of fluid passing through the valve will not be throttled—before the valve 5 is lifted from its seat. This is accomplished in the mechanism illustrated by providing an adjustable lost-motion connection 27 between the rod 26 and the bell-crank 25. The valve 4 is so arranged that the flow of fluid passing it into the chamber 10 will not be appreciably effected by its further movement after the valve 5 is open.

The apparatus thus far described is incapable of forcibly holding the valve 5 to its seat when the valve is closed, or during normal loads on the turbine; and consequently I provide a mechanism for performing this function and holding the valve 30 forcibly to its seat for the purpose of preventing leakage of motive fluid through it. To this end, I provide a piston 28 on the valve rod 23 of the valve 5 and locate it within the cylinder 24. The cylinder 24 is 35 formed in a cover 29 of the chamber 10 and is closed at its upper end by a head 30, through which the stem 23 projects. The upper portion of the cylinder 24, above the piston 28, communicates with the chamber 9 40 through piping 31; and the lower portion, below the piston, communicates with the chamber 10 through a passage 32 provided in the cover 29. With this arrangement, one side of the piston 28 is always subjected to the fluid pressure in the chamber 9 and the other side is always subjected to the pressure in the chamber 10. This operation of the apparatus is as follows: During normal loads on the turbine, the function 45 of governing is imposed on the valve 4 and consequently it operates to proportion the amount of fluid delivered to the turbine through the port 13 in accordance with the load demands. This is accomplished by 50 causing the valve 4 to occupy different positions corresponding to the varying speeds of the turbine and to throttle the flow of steam from the chamber 9 to the chamber 10. By throttling the flow of fluid in this 55 60 65 70 75 80 85 90 95 100 105 110 115 120 125 130 135 140 145 150 155 160 165 170 175 180 185 190 195 200 205 210 215 220 225 230 235 240 245 250 255 260 manner, the pressure in the chamber 9 is 65 maintained above the pressure in the chamber 10, and consequently the fluid pressure in the cylinder 24 above the piston 28 pre-ponderates over the fluid pressure below the piston, and operates to hold the valve 5 70 firmly on its seat. As the load on the turbine increases, the valve 4 is moved by the operation of the governor, to open the port between the chambers 9 and 10 greater and greater amounts and to decrease the throttling of the fluid entering the chamber 10. 75 At full load on the turbine, the valve 4 is fully open and it does not throttle the flow of fluid into the chamber 10, and consequently the pressures in the chambers 9 and 80 10 are approximately equal. Under these conditions, the closing force exerted on the valve 5 by the fluid pressure above the piston 28 is removed or overcome, since the pressure in the cylinder 24 below the piston 85 28 balances the pressure above the piston. As the load on the turbine increases above the normal load, the governor operates to open the valve 5 and to supply motive fluid to the turbine through the port 15 of the 90 valve casing, as well as the port 13.

It will be seen that my invention provides means for holding the valve 5 firmly on its seat with considerable force through a certain range of loads on the turbine, or 95 through a certain range of governor travel and for automatically removing or overcoming the closing force at the proper time; that is, at or just prior to the opening of the valve, or when full pressure is obtained in 100 the chamber 10.

In the apparatus illustrated, I have provided an adjusting screw or bolt for varying the lost-motion between the rod 26 and the bell-crank 25, and consequently for varying the operation of the valve 5. I preferably so adjust the apparatus that the valve 5 will start to open and to deliver motive fluid to the turbine at a time when the pressure in the chamber 10 is a few pounds less than in the chamber 9. By this arrangement, I shift the governing function from the valve 4 to the valve 5 as soon as the valve 5 is opened.

Having now described my invention, what I claim is:

1. In combination with a supply valve for an engine, means for exerting a closing force on said valve, means for overcoming or removing said force prior to the opening of said valve and governor controlled means 120 for opening said valve.
  2. In combination with a supply valve for an engine, fluid pressure means for imposing a closing force on said valve, means for automatically overcoming said force and 125 governor actuated means for opening said valve.
  3. A control mechanism for an engine

comprising a valve for delivering motive fluid to the engine, an auxiliary valve for delivering an auxiliary supply of motive fluid to the engine, a governor for controlling the operation of both valves, and pressure actuated means responsive to variations in the pressure of the fluid delivered by the first mentioned valve for imposing a closing force on the auxiliary valve while said valve is closed and for relieving said auxiliary valve of the closing force, prior to the opening of said valve in response to the operation of the governor.

4. In combination with a supply valve for an engine, fluid actuated means for imposing a closing force on said valve, governor controlled means for overcoming said force and means connected to and operated by the governor for opening said valve.

5. In combination with the supply valve of an engine, means subjected to opposing fluid pressures for exerting a closing force on the valve, governor actuated means for equalizing said opposing fluid pressures and means connected to and actuated by the governor for opening said valve.

6. In combination with a supply valve of an engine, a piston subjected to opposing fluid pressures for exerting a closing force on said valve, governor controlled means for equalizing said pressures and means connected to and actuated by the governor for opening said valve.

7. In combination with a supply valve of an engine, a piston subjected to opposing fluid pressures for exerting a closing force on said valve, a governor actuated valve for equalizing the pressures on said piston and means connected to and actuated by the governor for operating said valve.

8. In combination with the normal and overload valves of an engine, load responsive means directly connected to said valves and fluid actuated means for imposing a closing force on said overload valve during normal loads on the engine and for overcoming said force during full and overloads on said engine.

9. In combination with the normal and overload valves of an engine, a governor connected to said valves and having connection therewith for opening the normal load valve and for opening the overload valve after the normal load valve is open and fluid actuated means for imposing a closing force on said overload valve and for overcoming said force during the operation of said overload valve.

10. In combination with a normal and overload valve of an engine and a governor, means connecting the governor and the valves for operating both of said valves in series and means for imposing a closing force on said overload valve while it is in-

operative and for overcoming said force 65 during its operation.

11. In combination with a normal and overload valve of an engine, a governor, means connecting the governor and the valves for operating both of said valves in 70 series and means for imposing a closing force on said overload valve while it is inoperative and for overcoming said force prior to the opening of said valve.

12. In combination with the normal and 75 overload valves of an engine, speed responsive means for opening said normal load valve and for opening said overload valve after said normal load valve is opened and means subjected to opposing fluid pressures 80 for exerting a closing force on said overload valve while said valve is inoperative.

13. In combination with the normal and overload valves of an engine, a governor for controlling the operation of the valves, a 85 piston for exerting a closing force on said overload valve, means for admitting fluid pressure from the valve chest of said normal load valve to one side of said piston, and means for admitting fluid pressure from 90 the valve chest of said overload valve to the other side of the said piston.

14. The combination of a supply valve and an overload valve on an engine, of a speed responsive means connected to the 95 supply valve, a lost-motion connection between said speed responsive means and the overload valve, and means for imposing a closing force on the overload valve during normal loads on the engine and for overcoming 100 said force during full and overloads on said engine.

15. A turbine control mechanism, comprising a valve for delivering motive fluid to the turbine, a second valve for delivering 105 motive fluid to the turbine, a governor controlling the operation of both the valves to successively open and close said valves in response to variations in the load on the turbine, and pressure actuated means, responsive in operation to the operation of the first mentioned valve for imposing a closing force on the second valve prior to the opening of said second valve in response to the operation of the governor and for relieving said second valve of the closing 115 force, while it is in operation in response to the operation of the governor.

16. A control mechanism for a turbine, comprising a valve for delivering motive 120 fluid to the turbine, a second valve for delivering motive fluid to the turbine, speed responsive means for successively opening and closing said valves in response to variations in the speed of the turbine, and means 125 subjected to the pressure of fluid delivered to and the pressure of fluid delivered by said first mentioned valve for imposing a

closing force on the second valve while said second valve is closed and for relieving the second valve of the closing force while it is delivering motive fluid to the turbine in response to the operation of the speed responsive means.

In testimony whereof, I have hereunto

subscribed my name this 26th day of August 1910.

FRANCIS HODGKINSON.
